VALVE OPERATING DEVICE

Elmer F. Fisher, Auburn, Mass., assignor of one-half to James G. Veine, Worcester, Mass.

Application March 13, 1933, Serial No. 660,505
Renewed December 4, 1935

2 Claims. (Cl. 123—188)

The principal objects of this invention are to provide means for eliminating noise in the valve action of an internal combustion engine of the type in which the valves are in the cylinder head; 5 to prevent the valve stem from wearing off on one side on account of getting out of central vertical position; to eliminate the sticking of the valves, and to accomplish these objects with a minimum amount of attention and lubrication.

10 Other objects and advantages of the invention will appear hereinafter.

Reference is to be had to the accompanying drawing, in which

15 Fig. 1 is a vertical sectional view of a valve operating mechanism embodying the valve mechanism constituting a preferred embodiment of this invention, and

Fig. 2 is a side view of the top of the valve rod. The method of operating the valve in a cylinder head of the above description, which is commonly used, results in the production of noise after the parts have worn a little and got out of adjustment. This results in additional wear and improper action to the valve. Furthermore, 25 these valves have a tendency to get out of place to the extent of tilting slightly, thereby wearing the stem on one side. After being used awhile the surface is worn off one side of the valve stem and the valve does not seat properly and, furthermore, 30 more, it is a difficult thing to repair the valve.

This invention is designed to obviate these disadvantages. The power, of course, for operating the valve is obtained from the cam 10 on the cam shaft 11 on which rests a push rod lifter 12. 35 This push rod lifter is cup-shaped and has a concave recess 13 in the bottom in which rests the globular end of a push rod 14. This recess is at the bottom of the cup-shaped rod lifter 12 and consequently always contains oil so that there is an oil cushion at this point. In the push rod 40 lifter is a hollow cylinder 15, shorter than the lifter, through which the push rod passes and which supports a spring 16. This construction leaves a recess in the top of the push rod lifter 45 for receiving the bottom of the spring. The spring is mounted under a recessed washer 17, which bears against a collar 18 fixed to the push rod. In this way there is a yielding spring action to force the push rod up.

50 The push rod, of course, engages the rocker arm 19, preferably through an adjusting screw 20. This rocker arm bears on the top of the valve stem 21 which carries the valve 22 integral with it.

55 The valve stem is located in a cast iron sleeve

23 running in a cast iron guide 24. The guide has a circular boss 25 resting on the engine head and is stationary. The sleeve has a slidable fit in the guide and on the valve stem and it is provided with an integral spring seat 26 at the top. 5 The sliding fit of the sleeve on the valve stem is for the purpose of facilitating the removal of the sleeve when the valve stem key 29 is withdrawn.

Resting on the engine head and engaging the 10 bottom of this seat is a spring 27 materially stronger than the spring 16. The spring seat 26 is recessed to receive the valve stem key 29 which positively connects the valve stem and sleeve, but is removable to permit the sleeve to be re- 15 moved upwardly.

On account of the design of the cast iron sleeve 23 with an integral spring seat correct distribution of the heat is facilitated. The guide 24 being stationary constitutes a sufficient guide for 20 the sleeve 23 and together they prevent the tilting of the valve stem and the valve and necessitates the valve working on a vertical line at all times. This prevents the wear of the side of this stem. 25

The prevention of noise is further assisted by the spring 16 resting in what amounts to a recess in the top of the push rod lifter over the cylinder 15 and exerting upward pressure against the washer 17 and collar 18. This takes up the slack 30 at the points 30 and 31 where the rocker arm or its adjusting screw engages vertically operating rods. This also transfers the clearance to the concave surface 13 where the action is cushioned by the oil necessarily draining down the rod into 35 this concave surface.

In this way a noiseless action is secured even after the parts are worn and an integral spring seat 26 is provided which prevents spring vibration. 40

Although I have illustrated and described only one form of the invention, I am aware of the fact that modifications can be made therein by any person skilled in the art without departing 45 from the scope of the invention as expressed in the claims. Therefore, I do not wish to be limited in this respect, otherwise than as set forth in the claims, but what I claim is:—

1. The combination with an internal combustion engine valve, its stem and rocker arm, of a stationary guide, a sleeve having a sliding fit in the guide and on the stem and provided at the top with an integral spring seat, the stem and sleeve being connected to move together, and a 50 55

spring engaging the seat for holding the valve yieldingly against the seat.

2. The combination with an internal combustion engine valve and its stem, of a cylinder head in which the valve is located, a guide spaced from the stem and normally resting fixedly on said head, a sleeve having a sliding fit in the guide and normally fixed to, but removable from the

stem, and capable of moving longitudinally with the stem, a spring seat fixed to the stem, means for moving the stem and sleeve longitudinally, and a spring between the head and the seat on the sleeve for holding the sleeve and valve stem 5 outwardly.

ELMER F. FISHER.
